(57) **CLAIM**

The ornamental design for a loudspeaker as shown and described.

DESCRIPTION

FIG. 1 is a top perspective view of a first embodiment of a loudspeaker showing the new design;

FIG. 2 is a front elevational view thereof;

FIG. 3 is a rear elevational view thereof;

FIG. 4 is a side elevational view thereof;

FIG. 5 is an opposite side elevational view thereof;

FIG. 6 is a top view thereof;

FIG. 7 is a bottom view thereof;

FIG. 8 is a top perspective view of a second embodiment of a loudspeaker showing the new design;

FIG. 9 is a front elevational view thereof, with the handle in a folded, rear position;

FIG. 10 is a rear elevational view thereof;

FIG. 11 is a side elevational view thereof;

FIG. 12 is an opposite side elevational view thereof;

FIG. 13 is a top view thereof;

FIG. 14 is a bottom view thereof;

FIG. 15 is a top perspective view of a third embodiment of a loudspeaker showing the new design;

FIG. 16 is a front elevational view thereof;

FIG. 17 is a rear elevational view thereof;

FIG. 18 is a side elevational view thereof;

FIG. 19 is an opposite side elevational view thereof;

FIG. 20 is a top view thereof; and,

FIG. 21 is a bottom view thereof.

The broken lines illustrate portions of the loudspeaker that form no part of the claimed design.

1 Claim, 21 Drawing Sheets
